UNITED STATES PATENT OFFICE

JOSEPH H. THORNLEY, OF CHICAGO, ILLINOIS, ASSIGNOR TO WESTERN FOUNDATION COMPANY, OF CHICAGO, ILLINOIS, A CORPORATION OF ILLINOIS

METHOD OF MAKING PILES IN PLACE

Application filed November 2, 1927. Serial No. 230,434.

The present invention pertains to cast-in-place concrete piles and to an improved method of making the same. More specifically, the invention relates to that type of cast-in-place pile having an enlarged lower end or pedestal portion.

One of the objects of the invention is to provide an improved method of expanding or forcing the concrete outwardly at the bottom of the hole in the formation of the enlarged pedestal portion. According to this method of forming the pedestal portion, the expansive pressure is applied to the concrete in such manner that the major portion of the pressure acts laterally and downwardly, so that the reaction pressures of the soil against the pedestal portion will be in the proper direction for giving the maximum load bearing value to the finished pile.

Another object of the invention is to provide an improved method of bonding the column portion of the pile to the expanded pedestal portion. According to this method, the column portion of the pile has a "socketed bonding" in the pedestal portion of the pile, i. e., in the formation of the pedestal portion a vertical socket is formed therein in which the column portion of the pile is cast. In the preferred construction, the column portion of the pile comprises a corrugated tubular shell which extends down into this socket, whereby the corrugations of the shell establish an interlocking bond between the pedestal portion and column portion of the pile.

Other objects and advantages of the invention will appear in the following description of the preferred manner of carrying out my invention. In the drawing accompanying this description:

Figures 1, 2, 3 and 4 are vertical sectional views through the lower portion of the hole in which the pile is to be cast, illustrating successive steps in the formation of the pile; and

Figure 5 is a similar sectional view showing the lower portion of the completed pile.

The hole in which the pile is to be cast is sunk in any preferred manner such as by driving, jetting or digging, depending upon the character of the soil through which the

operation is carried. The present invention is not concerned with the method of sinking the hole, it being desirable, however, that a suitable casing line the hole after its completion, such casing either being carried down progressively with the sinking of the hole or being thereafter inserted.

Referring to Figure 1, the hole is indicated at 8, and the casing referred to is indicated at 9. After the hole has been sunk to the desired depth, and with the lower end of the casing 9 sustaining the side walls of the hole against collapse, a charge of concrete 11 is dumped into the lower end of the casing. This charge is sufficiently large to form the main body of the pedestal portion. A ram or core 12 is then lowered into the casing to bring its lower end into contact with the charge of concrete 11. If desired, the charge may be tamped lightly a few times by the core to compact its mass. The next step in the operation is illustrated in Figure 2, and consists in drawing the casing 9 upwardly to bring its lower edge into proximity to the lower end of the core or ram 12, meanwhile holding the core pressed downwardly against the top of the charge of concrete 11. The weight of the core will ordinarily be sufficient to hold it down upon the concrete, but if there is any tendency for the core to rise with the casing such is overcome by holding a stationary abutment against the upper end of the core, in a manner well known. As the casing is pulled upwardly, the concrete will expand outwardly into the space occupied by the casing, the ram 12 following the slight downward recession of the top of the concrete charge as this outward expansion takes place.

As shown in Figure 3, the upper end of the casing is provided with the usual hoisting collar 13, with which any suitable hoisting tackle may be connected for lifting the casing. It will be evident that by thus lifting the casing and holding the ram in place, the pedestal forming charge of concrete 11 will be stripped out of the casing, remaining in the bottom of the hole 8 and coming into direct contact with the side walls thereof. The density of the concrete will prevent any pos-

sibility of the sides of the hole collapsing inwardly during the lifting of the casing.

The next step in the operation is illustrated in Figure 3, and consists in forcing the core and casing downwardly into the charge of concrete, the core and casing operating as a unitary spreading or pressure member. To facilitate concurrent downward movement of the core and casing the upper end of the core is provided with a head 14 which is adapted to bear upon the hoisting collar 13 of the casing when the lower ends of the core and casing are in proximity to each other, as shown in Figures 2 and 3. By transmitting driving blows to the head 14 the core and casing will move downwardly as a unit through the engagement of the head 14 with the collar 13. In such downward movement, the charge of concrete will be crowded outwardly against the side walls of the hole 8, compressing the soil outwardly to enlarge the hole, and resulting in the concrete assuming the enlarged or bulb-shaped formation indicated at 11' in Figure 3. The descent of the core and casing is preferably limited so that they will not pass entirely through the concrete, but will leave a considerable thickness thereof at the bottom of the pedestal formation 11'. The result of this ramming operation is to expand the concrete outwardly, as above described, and to produce a longitudinal socket 15 in the pedestal formation, which socket extends down axially from the top of the pedestal to a point adjacent to the bottom thereof.

Certain important advantages accrue to this method of expanding the concrete. Heretofore, the practice most generally followed has been to confine a charge of concrete within the lower portion of the casing, and to force such charge down out of the end of the casing by downward movement of a ram within the casing. Sufficient pressure is exerted downwardly on the charge of concrete to compel it to flow out of the casing and to expand outwardly below the end of the casing into pressure contact with the earth walls, the fluid pressure of the concrete compressing the earth walls and enlarging the bottom of the hole sufficiently to produce the enlarged pedestal formation. This prior method is based upon a fluid flow of the concrete, requiring a comparatively wet mix thereof, such fluid flow resulting in the pressure imparted to the charge being transmitted substantially equally in all directions. Hence a considerable part of the pressure acts upwardly on the soil superposed over the pedestal formation, and, in consequence, the reaction of this superposed soil is downwardly, which detracts from the load bearing value of the pile in so far as carrying compression loads is concerned.

Such objection is avoided in the practice of the present method. Owing to the fact that the expansion of the concrete outwardly results more by virtue of the physical displace-

ment of the concrete through the direct mechanical spreading action of the core and casing, as distinguished from a fluid flow of the mass, there is very little tendency for the concrete to establish upwardly acting pressures against the soil superposed over the pedestal formation. The mechanical displacement of the concrete creates outwardly and downwardly acting pressures therein, which establish reaction pressures in the soil acting inwardly and upwardly with respect to the pedestal formation, thereby giving a firm anchorage to the pedestal and giving a maximum load bearing value to the pile. Moreover, the present method results in the formation of a long socket in the pedestal, as above remarked, which socket is a desirable feature for anchoring the column portion of the pile, as I shall now describe.

After the core and casing have been driven down into the concrete to the desired depth, the core is withdrawn, leaving the casing within the pedestal formation in order to maintain the formation of the socket 15 against the inwardly acting pressure of the concrete. The next step in the operation is illustrated in Figure 4, and comprises lowering a light tubular shell 16 within the casing, the lower end of such shell being preferably brought to bear upon the concrete at the bottom of the socket 15. This shell is preferably annularly corrugated to establish an interlocking bond between the concrete and corrugations, but, of course, a smooth sided shell may be employed in lieu of the corrugated one. After the shell 16 has been placed in position, additional concrete is dumped into the interior of the shell, preferably to fill the same completely. Such additional concrete is indicated at 17 in Fig. 5. Preparatory to dumping this additional concrete, any suitable reinforcing means may be inserted in the shell, represented, for example, by the relatively heavy bar indicated at 18 in Figure 5. The outer casing 9 forms no part of the completed pile, and is withdrawn either before the additional concrete 17 is dumped into the shell 16, or after the shell has been filled with concrete. Where the soil is of such character that it is possible that the earth pressure might collapse the light shell 16, it is, of course, desirable to retain the casing 9 in the ground as a protecting element until the light shell has been filled with concrete.

The withdrawal of the casing allows the concrete in the pedestal portion to move back into direct adhesive contact with the corrugations of the light shell. Thus as soon as the concrete sets the pedestal portion 11' has interlocking engagement with the shoulders 16' formed by the annular corrugations in the shell. Similarly the concrete 17 within the shell has interlocking engagement with the inner shoulders formed by the annular corrugations, and thus the pedestal portion 11' and

the column portion 17 have bonded engagement through the walls of the shell throughout the entire length of that portion of the shell which is embedded in the pedestal.

5 Cementitious bonding will also occur between the lower end of the column portion and the lower stratum extending across the bottom of the pedestal portion. It will be observed that by forming the socket 15 in the pedestal portion, the reinforcing means 18 can be extended down into the body of the pedestal portion so that the stresses transmitted to this reinforcing means will be distributed throughout substantially the entire body portion of the 15 pedestal.

It will be observed that at no stage in the operation of casting the pile is there any opportunity for sub-surface water to enter between the pedestal and the column, or for such 20 water to enter or have contact at any other point where it might deleteriously affect the casting of the pile. The long length of bonded joint between the column portion and pedestal portion gives a high tensile strength 25 to the finished pile, and it will be observed that by extending the shell 16 down into the pedestal portion there is no possibility of upwardly acting earth stresses causing the column portion to separate from the pedestal 30 portion before the concrete has set.

While I prefer to construct the column portion of the pile as a cast-in-place structure consisting of the shell 16 and concrete filling 17, nevertheless it will be understood that 35 some of the advantages of the invention can be realized by constructing the pedestal portion in the manner above described and then seating a pre-cast concrete pile, or any other type of completed pile within the socket 15 40 for bonding with the pedestal portion.

What I claim as my invention and desire to secure by Letters Patent, is—

1. The method of forming cast-in-place piles which comprises depositing a charge of 45 concrete in the hole in which the pile is to be formed in direct contact with the earth walls thereof, and ramming a core and casing down into said charge to expand the latter outwardly and to form a vertical socket within 50 the expanded charge of concrete, which socket is retained against collapse by said casing when said core is withdrawn.

2. The method of forming cast-in-place piles which comprises depositing a charge of 55 concrete in the hole in contact with the earth walls thereof, ramming a core and casing down into said charge for expanding the latter outwardly to form an enlarged pedestal portion having a vertical socket therein, with- 60 drawing the core while said casing maintains the form of said socket, and completing the pile with the column portion thereof extending down into said socket.

3. The method of forming cast-in-place 65 piles which comprises depositing a charge of

concrete in the bottom of the hole in which the pile is to be formed, ramming a core and casing down into the charge to expand the latter outwardly around the outer sides of the casing in the form of an enlarged pedestal 70 portion, withdrawing said core while retaining said casing within said pedestal portion, lowering a shell within said casing to have its lower end extend into said pedestal portion, dumping concrete into said shell, and 75 withdrawing said casing.

4. The method of forming cast-in-place piles which comprises sinking a hole in which the pile is to be formed, extending a casing down into said hole adjacent to the bottom 80 thereof, depositing a charge of concrete within said casing, raising said casing a predetermined distance to allow the concrete to contact directly with the earth walls at the bottom of the hole, driving said casing with 85 a core therein down into said charge of concrete for expanding the latter outwardly and for forming a vertical socket in said expanded portion, withdrawing said core while retaining said casing in said expanded portion to 90 maintain the form of said socket, lowering a shell within said casing to have its lower portion extend into said socket, dumping concrete into said shell and withdrawing said casing after said shell has been lowered into 95 said socket.

5. The method of forming cast-in-place tension resisting piles which comprises sinking a hole in which the pile is to be formed, carrying a casing downwardly in said hole 100 to line the sides thereof substantially to the bottom of said hole, dumping a pedestal forming charge of concrete into said casing, placing a core within said casing to bear upon said charge of concrete, raising said casing 105 a predetermined distance while said core forces the concrete out of the lower end of said casing into direct contact with the earth walls at the bottom of the hole, driving said core and casing downwardly as a unit into the charge of concrete, thereby spreading the charge outwardly against the earth walls for producing an enlarged pedestal portion and also forming a socket extending down into 110 said pedestal portion, withdrawing said core 115 while retaining said casing substantially in its driven position for sustaining the side walls of said socket, lowering a corrugated shell within said casing to have its lower end extend down approximately to the bottom 120 of said socket, placing reinforcing means within said shell, dumping additional concrete into the same for substantially filling said shell, and withdrawing said casing after said shell has been lowered into said socket. 125
